STENCIL SHEET FOLDER

David H. Robinot, New York, N. Y.

Application December 12, 1933, Serial No. 701,965

11 Claims. (Cl. 41—3.5)

This invention relates to stencil sheets of the kind suitable for use in connection with duplicating machines or the like and in which the stencils or matter to be reproduced are "cut" or produced by a typewriting machine or other suitable means.

As is well known in the art, stencil sheets suitable for use in connection with duplicating machines are made of light flimsy paper easily rumped, creased or otherwise injured during the handling thereof and when transported or stowed away for use.

In order to facilitate proper duplication, to avoid waste, and to provide for the repeated use of the same sheet, it is essential that the stencil sheet be at all times preserved and maintained in a smooth state, unimpaired by rumples, creases and tears.

To this end, an object of my present invention is to provide a folder or envelope by means of which to preserve and protect the stencil sheet both before and after using the same. Another object is to achieve this end in a simple, practical and efficient way, and in such manner as to make it easy and convenient to stencilize or type the stencil sheet with the aid of a backing sheet arranged to form an integral part of the folder itself and which during the typing operation forms a support in the usual way for the stencil sheet.

A further object of my invention is to provide for the stencil sheet a protective folder of the character described which is made with a recording surface or space adapted to exhibit either a notation place thereon identifying the stencilized stencil sheet, or a copy of the address, circular, or of any print or imprint written, typed or drawn over the stencilized stencil sheet which is contained in the folder.

A further object of my invention is to provide the protective folder with an interleaved portion which performs the function of a heading or collar for holding the stencil sheet in a smooth spread-out condition between the two integrally connected sides of the folder. This heading portion, integral with the folder, is detachable therefrom along a line in order to provide for the use of the stencil sheet in connection with a duplicating machine. After having been detached, the heading portion is, at will, replaceable in its interleaving position, suitable means in the form of an integral interlocking flap being provided for detachably securing the same in such position firmly to the folder.

With the foregoing and other objects in view,

the invention consists of the novel construction, combination and arrangement of parts as hereininafter more fully described, and illustrated in the accompanying drawing, wherein is shown one practical example of the invention.

5

In the drawing, wherein like reference characters denote corresponding parts throughout the several views:—

Figure 1 represents a plan view of the folder in spread-out or extended condition, looking at the inner face thereof, with a portion of the stencil sheet broken away;

Fig. 2 is a similar view, but showing the heading portion and accompanying stencil sheet folded inwardly upon the backing sheet, ready for insertion in a typewriter;

Fig. 3 is a fragmentary plan view of the protective folder in folded condition, showing the exterior of the backing sheet or side, with the interlocking flap of the fronting or counter side engaged with the backing sheet;

Fig. 4 is a view similar to that of Fig. 3, but showing the exterior of the fronting or counter side;

Fig. 5 is a cross section taken on the line 5—5 of Fig. 4; and

Fig. 6 is a cross section taken on the line 6—6 of Fig. 3.

In describing my invention, the terms and expressions which I use are employed as terms of description and not of limitation, and I have no intention, in the use of such terms and expressions, of excluding any equivalents of the features shown and described or portions thereof.

The body of my folder may consist of any flexible paper or similar material suitable for use as a backing and protective covering for the soft flimsy sheet 10 of stencil paper, and in the illustrated exemplification, the body of the folder is represented as comprising a backing sheet or side 11 and a fronting sheet or side 12. These two sheets or sides, 11 and 12, may be of the same size and they are made in one piece, their integral connection being at the foot end of the folder along a transverse fold or turn line 13 which acts as a hinge to provide for opening and closing movement of the folder.

Integrally associated with the head end of the backing sheet 11 is a heading or collar 14 which is movable on a perforated turn or fold line 15. To this heading or collar, the stencil sheet 10 is attached at its head end by any suitable means, as for instance by paste or gum; and the combined length of these two parts, when so united, is approximately equal to the length of the back-

55

ing sheet 11 between the turn or hinge lines 13 and 15, and in this connection it may be pointed out that when the heading 14 is moved into a position to overlie the inner face of the backing sheet 11 with the accompanying stencil sheet superposed and smoothly spread out as shown in Fig. 2, the free inner end 16 of the stencil sheet should come slightly short of the turn or hinge line 13 so as not to be rumped or creased during the opening and closing movement of the folder.

Integrally associated with the head end of the fronting sheet or side 12, is a flap part 17 which is movable on a transversely extending turn or fold line 18 the function of which is that of a hinge. In the present exemplification, this flap part 17 is represented as being formed with three spaced-apart projections or tongues 19, 20 and 21. When the folder is closed, that is to say when the fronting sheet 12 is superposed upon the stencil sheet 10 and its heading 14, or vice versa, when the backing sheet 11 with the parts 16 and 19 properly overlying the inner face thereof, is superposed upon the fronting sheet 12, the flap part 17 may be moved across the head or perforated edge of the heading 14 and thence be applied flatwise alongside the outer face of the backing sheet 11, as shown in Fig. 3.

Means may be provided whereby to detachably secure the flap part 17 to the backing sheet 11 and also to the heading 14 when the folder is in the folded condition illustrated in Fig. 3. In the present embodiment, the means for this purpose consists in providing the backing sheet 11 and the heading 14 with corresponding slots or openings 22, 22, 23, 23 and 24, 24, which corresponding openings are shaped and spaced for receiving therethrough the respective tongues 19, 20, and 21 of the flap part 17. As illustrated in Figs. 3 and 6 the tongues are passed inwardly through their corresponding slots so that their free inner end portions can lie flatwise between the adjacent faces of the heading and fronting sheet whereby firmly and yet detachably to secure the backing sheet, the fronting sheet and the interleaving heading together at the head end of the folder.

As illustrated in Fig. 1, the inner face of the backing sheet may be provided with any suitable lining or marking as 25, or 26, or other figures or scales, designed to indicate to the typist where and how the stencil sheet should be "cut" to produce the desired stenciled sheet for duplicating purposes.

The outer face of the fronting sheet 12 affords a surface 27 whereon may be written or typed any suitable notation for identifying the stenciled stencil sheet within the folder; and, when desired, a copy of the circular or of any print or imprint, produced from the stencil within the folder, or any written or typed identification thereof, may be pasted upon the surface or space 27. With this arrangement for quickly identifying the stenciled sheet contained within the folder, much valuable time and labor can be saved, particularly in an office or place of business where hundreds and perhaps thousands of stenciled stencil sheets have been prepared. The heading or cover 14 to which the stencil sheet is attached is provided with spaced keyhole slots 28 or other openings suitably shaped for use in applying the heading to the carrier of the duplicating machine in the usual way. The flap part 17 and fronting sheet 12 adjacent the hinge line 18, and the backing sheet 11 adjacent the hinge line 15

are also preferably provided with keyhole slots 29, 29', and 30, respectively, which slots are positioned so that when the folder is closed and the flap part interlocked with the backing sheet and heading, the keyhole slots 29, 28, 30, and 29' will be in registration transversely of the folder, so that the folder, if desired, may be hung from suitable hooks, nails or the like, which are received in the registered slots.

From the foregoing description, taken in connection with the accompanying drawing, it will be understood that the backing sheet, heading for the stencil paper, fronting sheet and flap part may all be produced in one piece in which are provided the turn or hinge lines 13, 18 and 15, of which the last-named is preferably perforated. Assuming that these parts have been folded to produce the folder shown in Fig. 3 containing a stencil sheet 10 held by the interleaving heading 14, if it be desired to stencilize the stencil sheet, then the flap part is disengaged from the backing sheet and thereupon the fronting sheet and backing sheet may be opened and spread out in line as shown in Fig. 2, in which condition for the purpose of "cutting" the stencil the perforated end 15 can readily be inserted in the typewriter and through the manipulation of the platen roller of the typewriter in the usual way the stencil supported upon the backing sheet may be positioned as desired to carry out the stenciling operation, the fronting sheet during the stenciling operation trailing over the paper rest and behind the typewriting machine. Where it is not desired to perform a duplicating operation immediately after stencilizing the stencil paper, the parts for preserving and protecting the stenciled sheet may be folded up in folded condition as illustrated in Fig. 3. Whenever, however, it is desired to perform a duplicating operation, the heading with the accompanying stenciled sheet is detached from the backing sheet along the perforated line 15. After the duplicating operation has been performed, the heading with the accompanying stenciled sheet may be disposed in their original position between the backing and fronting sheets, the folder closed and the flap part interlocked with the backing sheet when the entity structure may be hung up or stowed away in any suitable place until it is again desired to make use of the stenciled paper in a duplicating operation. An important advantage of my improved stencil sheet folder resides in the fact that the stencil sheet is preserved and protected against rumpling or injury at all times, that the heading with the attached stencil sheet is readily detachable for the duplicating operation, and that after the duplicating operation the stenciled sheet can be preserved and protected for repeated use, and further that through provision of the space or surface 27 on the exterior face of the fronting sheet, either by a notation or by an attached copy or reproduction of the stenciled matter, the stencil which is contained within the folder may be fully identified.

As many changes could be made in the details of the above noted construction and many apparently widely different embodiments of this invention could be made without departing from the spirit and scope thereof; it is intended that all matter contained in the above description or shown in the accompanying drawing shall be interpreted as illustrative and not in a limiting sense.

I claim:—

1. A protective folder for a stencil sheet comprising a backing sheet, a fronting sheet integral therewith, a heading portion for holding the 5 stencil sheet between the backing and fronting sheets, said heading portion permanently carrying the stencil sheet and being integral with one of said sheets and detachable therefrom for removal with its stencil sheet, and separate means 10 for securing said heading portion in place between said backing and fronting sheets to at least one of the same and irrespective of whether or not said heading portion remains integrally connected or has been detached.

15 2. A protective folder for a stencil sheet comprising a backing sheet, a fronting sheet integral therewith at one end, a detachable heading portion integral therewith at a second end and adapted to hold a stencil between the two sheets, 20 and means movable to a position across said second end for retaining the heading portion against withdrawal.

25 3. A protective folder for a stencil sheet comprising a backing sheet, a fronting sheet integral therewith at one end, one of said sheets affording an exterior surface for carrying indicating media, a detachable heading portion integral with one of said sheets and movable to a position between the two sheets to hold a stencil between 30 the same, and means on one of said sheets for detachably connecting said portion to and between the two sheets.

35 4. A protective folder for a stencil sheet including a backing side, a fronting side integral therewith at one edge, a detachable heading portion integral with the backing sheet opposite said edge and movable to a position between the sheets to hold a stencil therebetween, and means integral with one of the sheets adapted to afford 40 and maintain an engagement with the other of the sheets and with said heading portion.

45 5. In combination with a flexible stencil sheet, a backing side therefor having an integral heading portion for the attachment of the stencil sheet said portion being detachable and adapted when attached and detached to rest against the inner face of the backing side, an integrally connected complementary fronting side for covering said portion when the latter rests against the 50 inner face of the backing side, a flap part carried by one of said sides and movable to a position upon the outer face of the backing sides, and means for detachably connecting said flap part with the backing side and also with said heading portion when the latter is attached and when it is detached.

55 6. In combination with a flexible stencil sheet, a backing side therefor having an integral heading portion for the attachment of the stencil sheet and detachable along a line, a complementary fronting side, a flap part carried by one of said sides and movable to a position alongside the other of the sides, and means for detachably connecting said flap part both to the other side 60 and to said heading portion, said means being

effective irrespective of whether or not the heading portion remains integral with, or has been detached from, the backing side.

7. In combination with a flexible stencil sheet, a backing side therefor having an integral heading portion for the attachment of the stencil sheet and detachable along a line, a fronting side having a flap movable to a position alongside the backing side, and means for detachably connecting said flap, backing side and heading portion comprising a tongue projecting from one of said parts, the other parts being provided with openings for receiving said tongue. 10

8. In a protective folder for a stencil sheet, the combination of backing and fronting sides connected at one end for opening and closing movement, a heading part for the stencil sheet associated with a free end of the backing side and movable to a position between the sides to hold the stencil therebetween, and means for detachably connecting the heading part with the 15 backing and fronting sides.

20 9. In a protective folder for a stencil, the combination of backing and fronting sides connected at one end for opening and closing movement, a heading part for the stencil sheet associated with a free end of the backing side and movable to a position between the sides whereby to hold the stencil sheet spread-out between the sides, and means for detachably connecting the heading part 25 in position between the backing and fronting sides comprising an integral projection on one of said parts, the other parts being provided with corresponding openings for receiving said projection. 30

35 10. In a protective folder for a stencil, the combination of backing and fronting sides connected at one end for opening and closing movement, a heading part for the stencil sheet associated with a free end of the backing side and 40 movable to a position between the sides whereby to hold the stencil sheet spread-out between the sides, and means for detachably connecting the heading part in position between the backing and fronting sides comprising an integral flap on the 45 fronting sheet, spaced integral tongues on the flap, and correspondingly spaced openings in the backing side and heading part for receiving said tongues.

50 11. A protective folder for a stencil sheet comprising a backing sheet, a fronting sheet, a heading portion, all integrally formed, the backing and fronting sheets being foldable together along a fold line and the heading portion being separable along a detachable line located opposite said 55 fold line, a stencil sheet attached to the heading portion and therewith disposable between said sheets to lie in extending relation from said detachable line toward said fold line, and means adapted to secure the backing sheet, fronting 60 sheet and heading portion together, comprising a projection on one of said parts and openings on the others of said parts for receiving said projection.

DAVID H. ROBINOT. 65
